BY

Geo. Himmel ATTORNEY.

UNITED STATES PATENT OFFICE.

SPENCER E. KLUCAS, OF BARRY, MINNESOTA.

END GATE.

Application filed July 28, 1926. Serial No. 125,437.

This invention relates to wagon end gate structures and pertains particularly to an improved means for locking such end gates in position.

5 A further object of the invention is the provision, in a manner as hereinafter set forth, of a wagon end gate formed in two sections which is adapted to be broken for the easy and quick removal of the end gates 10 of the wagon body.

Another object of the invention is the provision, in a manner as hereinafter set forth, of a two part hinged wagon body end gate having an improved type of reinforcing structure attached thereto and further having an improved construction of locking means associated with and operating upon the reinforcing structure to form the gate into a rigid body when in operative 20 position.

Further advantageous objects of the invention will become apparent as the description of the device proceeds and the construction and operation of the device will be 25 better understood from a consideration of the following detailed description taken in connection with the accompanying drawing forming a part of this specification, with the understanding, however, that the invention 30 is not confined to any strict conformity with the showing of the drawing but may be changed and modified so long as such changes and modifications mark no material departure from the salient features of the 35 invention as expressed in the appended claim.

In the drawing:—

Figure 1 shows in top plan, a portion of the rear of a wagon body, showing the end gate structure embodying this invention in 40 position.

Figure 2 shows the wagon body in end elevation with the gate structure in position upon the body.

45 Figure 3 shows the gate structure removed from the body and broken as it must be for insertion or removal, the gate being shown also in longitudinal section.

50 Referring now to the drawing in detail wherein like numerals of reference indicate corresponding parts throughout the several views, the numeral 1 indicates the bottom of a wagon body having the upstanding sides 2, each of which sides has secured to the inner face thereof adjacent the rear end the

vertical spaced parallel cleats 3 between which the ends of the wagon end gate are to be located.

The gate embodying this invention comprises two sections 4 and 5, arranged in end opposed relation and hingedly connected at these opposed edges by means of the hinges 6. The members or portions 4 and 5 are of a width equal to the height of the wagon sides 2 and when in alignment as shown in Figure 1, are in length equal to the width of the wagon body.

Each of the sections 4 and 5 of the gate has secured adjacent each end edge and transversely of the outer face thereof a cleat 7, one of the purposes of these cleats being to reinforce the sections to prevent the splitting of the same.

Extending longitudinally of the complete gate, is a steel frame composed of upper 75 and lower angle bars 8 which are connected at one end by the transverse angle bar 9.

As is clearly shown in Figure 2 those ends of the bars 8 remote from the connecting bar 9, overlie and are riveted or otherwise secured to the cleats 7 upon the gate portion 5 but are not connected to the cleats of the gate portion 4. As is also clearly shown, the reinforcing frame connecting bars 8 are of such length as to arrange the connecting bar 9 along the inner edge of that cleat 7 which is adjacent the free end of the gate portion 4, when the gate is in set up operative position. The connecting bar 9 of the gate reinforcing frame being an angle bar 80 85 and having one side thereof secured across the inner faces of the angle bars 8, has the other side thereof, when the gate is closed, positioned against the inner edge of the cleat 7 at the free end of the gate portion 4 and is therefore substantially flush with the outer face of this cleat.

Pivotedly secured to the central portion of the cleat 7 at the free end of the gate portion 4, is a latch member indicated generally by 100 the numeral 10. As shown this latch member comprises a substantially semi-circular plate 11 centrally pivotally secured by the bolt 12 to the outer cleat of the gate section 4, and extending from this plate 11 and held in offset parallel relation to the face thereof by means of the offset portion 13, is an arm 14.

As will be clearly seen from a study of Figure 1, the arm 14 of the latch structure 110

is so spaced from the plate portion 11 that it must be sprung slightly outwardly to pass over the edge of the outwardly projecting portion of the angle bars 8, when the latch 5 is swung to cause the circular portion of the plate to move to position over the bar 9 which is flush with the surface of the cleat 7 to which the plate is secured. From this it will be readily seen that when the latch 10 is swung to lock the free end of the gate reinforcing frame to the gate section 4, the outwardly sprung arm portion 14 of the latch will have frictional engagement with one of the bars 8 which will prevent the accidental movement of the latch and release of the arcuate portion of the plate from the bar 9. It is of course understood that the latch may be so swung that the arm 14 will be positioned between the bars 8 in which 20 position the only connection between the latch and the reinforcing frame will be between the bar 9 and the plate 11 but to ensure a tighter lock the arm 14 should be frictionally engaged over the edge of the extended portion of one of the bars 8. It will be also readily understood that by swinging the latch 10 to position the arm 14 vertically and parallel to the adjacent cleat 7, that the straight edge of the plate 11 will be brought 25 into alignment with the inner edge of the attached cleat to allow the bar 9 to pass the

latch when the gate is broken in the manner shown in Figure 3.

It will be, of course, understood that when the gate is in position, the free ends of the portions 4 and 5 thereof will be arranged between the cleats 3 upon the sides of the wagon body.

Having thus described my invention what I claim is:—

A wagon end gate of the character described, comprising a pair of sections hingedly secured in end opposed relation, a reinforcing frame comprising a pair of members arranged in spaced relation longitudinally 45 of the gate and a connecting member connecting the members together at one end of the frame, the other ends of the members being secured to a gate section, a latch carried by the other gate section adjacent the free end thereof and adapted to engage over said connecting member to lock the gate in operative position, and an actuating handle forming a part of said latch, said handle being designed to be sprung outwardly to pass over and frictionally engage one of said pair of members, to hold the latch against accidental displacement.

In testimony whereof, I affix my signature hereto.

SPENCER E. KLUCAS.
